UNITED STATES PATENT OFFICE.

ISADOR M. GOULD, OF PHILADELPHIA, PENNSYLVANIA.

DESIGN FOR A PICTURE-FRAME.

SPECIFICATION forming part of Design No. 35,992, dated August 12, 1902.

Application filed February 21, 1902. Serial No. 95,134. Term of patent 3½ years.

To all whom it may concern:

Be it known that I, ISADOR M. GOULD, a citizen of the United States, residing at Philadelphia, county of Philadelphia, and State of Pennsylvania, have invented a new, original, and ornamental Design for a Picture-Frame, of which the following is a specification, reference being had to the accompanying drawings, forming a part thereof.

Figure 1 is a front view of the picture-frame. Fig. 2 is an edge view looking at the bottom of Fig. 1.

As shown in the drawings, the leading and material feature of my design consists of a picture-frame so constructed as to resemble or indicate a picket fence, the top cross-piece A representing the upper rail of the fence and the bottom cross-piece B representing the lower rail of the fence, while the vertical end posts C represent fence-posts, and the pointed ornaments D, extending upward from the upper rail and downward from the lower rail, represent pickets. The space included be-

tween the upper and lower cross-piece B and the end posts C is intended for the picture or 25 pictures and is divided into a number of divisions by means of T-shaped cross-pieces E. Upon the face of the upper and lower end of the cross-pieces C are represented horseshoes, as indicated at F, and in the center of the 30 upper cross-piece A is represented a horsebit G, and upon the lower cross-piece B is represented a riding-whip H.

Having thus described my invention, what I claim as new, and desire to secure by Letters 35 Patent, is—

The ornamental design for a picture-frame, as herein shown and described.

In testimony whereof I have hereunto affixed my signature in the presence of two sub- 40 scribing witnesses.

ISADOR M. GOULD.

Witnesses:

H. B. HALLOCK,
L. W. MORRISON.
